UNITED STATES PATENT OFFICE.

WARREN HIBBARD, CHARLES HIBBARD, AND SUMNER HIBBARD, OF
SANDYHILL, NEW YORK.

EXPLOSIVE-ENGINE.

SPECIFICATION forming part of Letters Patent No. 746,701, dated December 15, 1903.

Application filed August 13, 1902. Serial No. 119,500. (No model.)

To all whom it may concern:

Be it known that we, WARREN HIBBARD, CHARLES HIBBARD, and SUMNER HIBBARD, citizens of the United States, and residents of 5 Sandyhill, in the county of Washington and State of New York, have invented a new and Improved Explosive-Engine, of which the following is a full, clear, and exact description.

The invention relates to two-cycle explosive- 10 engines; and its object is to provide certain new and useful improvements in explosive- engines whereby the explosive mixture drives a charge of fresh air into the working cylinder to scour or clean the same of all products 15 of combustion left by a former explosion, at the same time extinguishing any possible flame which may be contained in the working chamber.

A further object of the invention is to provide 20 a mixture which has its component parts regulated according to the work to be performed by the engine.

The invention consists of novel features and 25 parts and combinations of the same, as will be fully described hereinafter and then pointed out in the claims.

A practical embodiment of the invention is represented in the accompanying drawings, forming 30 a part of this specification, in which similar characters of reference indicate corresponding parts in all the views.

Figure 1 is a side elevation of the improvement with part of the cylinder in section. Fig. 2 is an enlarged sectional side elevation 35 of the air and gas mixing device, and Fig. 3 is a rear elevation of the same with part in section.

In the cylinder A of the explosive-engine reciprocates in the usual manner a piston B, 40 connected by pitman and crank with the main driving-shaft of the engine. The upper end of the cylinder A forms the working chamber A', and the lower end thereof, as well as the crank-casing, forms a compression 45 and storage chamber A² for the explosive mixture. To one side of the cylinder A is secured an air and gas mixing device C, formed with a channel D, having one end, D', registering with the port a, opening into the working 50 chamber A' near the lower end thereof, and the other end, D², of the channel D registers

with the port b, extending through the cylinder-wall to connect with the chamber A², as plainly indicated in Fig. 1. An inwardly-opening spring-pressed air-inlet valve E is arranged on 55 the top of the mixing device C to let air into the channel D near the end D' thereof, and in the bottom of the said mixing device C is arranged a gas-inlet valve F for admitting gas into the channel D between the air-inlet 60 valve E and the end D² of the channel D. The air-inlet valve E is normally held to its seat by a spring E', and the stem E² of the said valve is adapted to engage the stem F' of the gas-inlet valve F, so that during the 65 suction period the valve E opens and by its stem E² causes the valve F to open. Thus air is admitted into the channel D near the end D', and gas is admitted at the same time to the said channel near the end D², it being 70 understood that a portion of the air admitted passes through the channel in the direction of the arrow a' to mix with the gas from the valve F to finally pass through the port b into the chamber A². When the valve E closes 75 at the end of the suction period, then that portion of the channel D between the end D' and the valve F is filled with pure air, and when the piston B is on the working stroke and forces the mixture from the chamber A² 80 through the port b and channel D in the inverse direction of the arrow a' then this charge of gas and air drives the air in the channel D through the end D' thereof and the port a into the working chamber A' to force 85 any products of combustion left by the previous explosion through the exhaust-port c to the outer air. Thus a charge of pure air passes in advance of the mixture into the cylinder, and consequently any flame that may 90 be left in the working chamber is extinguished previous to the explosive mixture of air and gas passing into the perfectly clean working chamber. A pipe G is connected with a suitable gas-supply and delivers the gas to an 95 inlet-valve H under the control of the operator, and from which passes the gas in the desired quantity through the valve F into the channel D. In the latter, between the air-inlet valve E and the gas-inlet valve F, is arranged a regulating-valve I, preferably in the shape of a winged valve, to regulate the

amount of explosive mixture passing to the working chamber of the cylinder.

If the work to be performed by the engine is comparatively light, the valves G and I are set correspondingly to admit a comparatively small and weak mixture to the explosive-chamber; but in case the work to be performed by the engine is heavier the said valves G and I are opened more fully to admit a richer 10 and larger quantity of air and gas to the working chamber of the cylinder. The engine is provided with the usual igniting device (not shown) to ignite the explosive mixture at the proper time in the working chamber.

15 Having thus described our invention, we claim as new and desire to secure by Letters Patent—

1. An explosive-engine comprising a cylinder, a piston moving therein, a gas-mixing device mounted adjacent to said cylinder, and having channels communicating therewith, an air-inlet valve for said mixing device, a valve-controlled gas-inlet at the opposite side of the device from the air-inlet, means connected with the air-inlet valve and contacting with the gas-inlet valve for opening the latter when the air-valve is opened by the movement of the piston, the construction being such that a charge of pure air will be forced into the working chamber of the cylinder prior to the entrance of the unexploded charge, substantially as set forth.

2. An explosive-engine, provided with a mixing device having a channel connected at 35 one end with the working chamber of the cylinder and at the other end with the storage and compression chamber for the gas and air, an air-inlet in the said channel at or near the entrance of the channel into the working

chamber, and a gas-inlet for the said channel 40 between the compression-chamber and the said air-inlet, devices for opening and closing both the air and the gas inlet simultaneously so that air is forced by the mixture into the working chamber to clean the same of any 45 products of combustion from a previous explosion, previous to the mixture passing into the working chamber, as set forth.

3. An explosive-engine, provided with a mixing device having a channel connected at 50 one end with the working chamber of the cylinder and at the other end with the storage and compression chamber for the gas and air, an air-inlet in the said channel at or near the entrance of the channel into the working 55 chamber, a gas-inlet for the said channel between the compression-chamber and the said air-inlet, so that air is forced by the mixture into the working chamber to clean the same of any products of combustion from a previous 60 explosion previous to the mixture passing into the working chamber, a valve for regulating the amount of gas passing to the said gas-inlet, a regulating-valve in the said channel between the air-inlet and the gas-inlet, and means for actuating the valve of the gas-inlet to admit a charge of gas, simultaneously with the admission of air through the air-inlet, as set forth.

In testimony whereof we have signed our 70 names to this specification in the presence of two subscribing witnesses.

WARREN HIBBARD.
CHARLES HIBBARD.
SUMNER HIBBARD.
